UNITED STATES PATENT OFFICE.

JOHN M. ZWICKLE, OF ROANOKE, VIRGINIA.

SMOKING SET.

1,143,159.

Specification of Letters Patent. Patented June 15, 1915.

Application filed October 15, 1914. Serial No. 866,802.

To all whom it may concern:

Be it known that I, JOHN M. ZWICKLE, a citizen of the United States, residing at Roanoke, in the county of Roanoke and 5 State of Virginia, have invented certain new and useful Improvements in Smoking Sets, of which the following is a specification.

This invention relates to smoking sets and its object is to provide a neat, compact 10 and safe receptacle for unlighted cigars, cigarettes, etc., and a container for matches. It embraces also an improved method of holding lighted cigars or the like and at the same time provides an ash remover and 15 retainer that is cleanly and sanitary and may be readily cleaned. A humidor and a cigar-tip cutter are also provided.

With these and similar objects in view 20 my invention consists of the peculiar formation and the combination of parts as will be herein shown and claimed.

Referring now to the accompanying drawings wherein like parts are similarly designated, Figure 1 represents in perspective 25 view the smoker's set of my invention. Fig. 2 is an end elevational view, partly in section, of the same, and Fig. 3 an inverted plan view drawn to a reduced scale. Figs. 4 and 5 are perspective views of the removable cigar rest and ash remover.

The following description will explain 30 the construction and use of the various elements shown, the device consisting of an ornamental box or body portion 1 which may be of any desired shape, rectangular 35 being shown in the drawings. This box is closed on the bottom and on the four sides, the top however being open. It is divided into three general compartments by means 40 of the walls 2 and 3, the compartment 4 being intended for use as an ash receiver, the compartment 5 as a container for unlighted cigars or cigarettes, and the space 6 being adapted to serve as a match holder. 45 The dividing wall 2 I preferably make of asbestos or other insulating material so as to afford protection to the matches. In the present construction two metal walls are used and asbestos is packed between them.

50 In order to prevent fire from a lighted cigar getting into the unlighted cigar compartment or into the match compartment, the wall 2 is made to extend slightly above

the sides of the box. An opening 7 is provided in the outer wall of the box to expose the striking strip on the side of a commercial box of matches, such a box of matches being shown in position in the match holder. I provide also an additional striking strip 8 on the front of the box 60 which is made by roughening the metal of the box or by securing to it a piece of sand paper or similar material.

In the bottom of the compartment 5 I place a sponge 9 and immediately over this 65 a false bottom 10. This false bottom is provided with a plurality of holes and at the ends thereof the strip of metal forming this false bottom is bent down to form the legs 11. The sponge 9 is preferably secured 70 to the under side of this false bottom, the legs 11 thus serving to form spacers between the true bottom 12 and the false bottom 10, the sponge 9 occupying the space between. The false bottom 10 is made slightly smaller 75 than the compartment 5 so that it may be readily lifted out, and the sponge with it, in order to moisten the latter. The compartment 5 equipped with this moist sponge becomes a humidor and cigars, etc., kept 80 therein will be prevented from so rapidly drying out.

The compartment 4, which serves as an ash receiver, is provided with a cigar tray 85 13 and an ash remover 14. The cigar tray 15 is made of corrugated metal, the corrugations running up and down the cigar tray, transversely of its length, which slopes from the top of the box at the front at 16 to a lower height near the center of the 90 ash compartment at 17. By means of this inward declination the cigars will slide down a corrugation when laid on the same until stopped by striking the ash remover 14, and the possibility of a lighted cigar 95 falling on the floor will be greatly lessened. At the lower edge at 17, the corrugated cigar tray abuts the upwardly inclined ash remover 14 which is made of wire fabric or screen. This ash remover extends from 100 the point 17, or slightly below this point, to the upper rear edge 19 of the box 1, the plane thereof forming approximately a right angle with the plane of the cigar tray. When a cigar is placed on the tray 105 13 the lighted end strikes the screen or

ash remover 14 and the ashes are broken off and pass through the screen and into the ash receiver 4. Larger particles that fail to pass through the meshes of the screen will roll down the same and enter the ash compartment 4 through the slot 20 which is provided in the cigar tray for the purpose.

The cigar tray 13 and the ash remover 14 are permanently fastened together by means of suitable bars or braces 23 and 23^a and the whole forms a separable unit from the box portion 1 and is adapted to fit snugly and tightly therein. For supporting this separable unit I have shown the cigar tray as having a strip of the metal thereof bent over at 24, to embrace the upper front edge of the box. Loosely hinged at 18 to the under side of the screen 13 along the upper edge of the same is a flap or door 25 which normally hangs downward along the back of the box. In case, however, the outfit should be overturned the flap 25 will fall against the under side of the screen and blank off the same, preventing the spilling of ashes or refuse on the floor or table, this position of the flap being shown in Figs. 4 and 5 in the finely dotted lines.

In the bottom of the ash receiver 4 I provide an opening 21 which is normally closed by the door 22, which is secured by the pintle 22^a, the spring 22^b serving to hold this door in closed position. When it is desired to empty the ash receiver the entire device is held over any convenient receptacle and by opening the door 22, which opens outwardly, the refuse in the ash receiver will fall out.

At 26 I provide an opening in the front of the box, said opening being into the ash receiver compartment 4. This opening is normally closed by a cigar cutter blade 27 which is pivoted to the front wall of the box at 28, and having a notch 29 for the insertion of the cigar tip. By lifting up on the end 30 of this blade which extends outwardly through a slot 31 in the end wall of the box the cigar tip may be clipped off between the sharpened edge 32 of the blade 27 and a similar sharpened edge 33 on the box. The spring 34 is provided for returning the blade 27 to its normal position, which is the lower position shown in the drawings. The slot 31 is of such length that the blade 27 may be lifted entirely above the hole 26 which then serves to admit cigar or cigarette butts or the like, the blade 27 serving in its normal position to close this opening against the spilling of ashes in case of the overturning of the outfit.

At 35 I have provided an opening in the cigar tray which serves also to admit cigar stumps or the like.

I have thus described how I preferably construct my invention and it will be seen

that I have provided a neat substantial and sanitary arrangement for the convenience of smokers.

Having thus described my invention, what I claim is:

1. In a smoking set a box having an ash compartment therein, a cigar tray and an ash remover disposed over said ash compartment, said cigar tray being inwardly declined from the front and top of said box and abutting at its inner end said ash remover near the center of said ash compartment, said ash remover extending from adjacent the inner end of the said cigar tray to the rear and top of said box, the plane of said ash remover being disposed at substantially 90° from the plane of said cigar tray.

2. In a smoking set a box having an ash compartment therein, a cigar tray and an ash remover disposed over said ash compartment and being loosely attached thereto, said cigar tray being inwardly declined from the front and top of said box and abutting at its inner end said ash remover near the center of said ash compartment, said ash remover extending from adjacent the inner end of the said cigar tray to the rear and top of said box, the plane of said ash remover being disposed at substantially 90° from the plane of said cigar tray.

3. In a smoking set, an inwardly declining cigar tray and an inclined ash remover adjacent the inner end of said cigar tray, the inner end of said cigar tray abutting the said ash remover near its lower extremity, a portion of the material of the said cigar tray being cut away near its inner end to form an opening for the passage of ashes.

4. In a smoking set, a box having an ash compartment therein, an ash remover having openings therein disposed over the said ash compartment, and a depending flap hinged under the said ash remover, said flap being adapted to hang normally in an open position with respect to the openings through the said ash remover and being adapted further to fall against the under side of said ash remover and close the openings through the same when the said box is overturned.

5. In a smoking set, a box having an ash compartment therein, said ash compartment having a clean-out opening in the bottom thereof, and said opening being adapted to be normally closed by a spring controlled door, all in combination with a cigar tray and an ash remover disposed over said ash compartment, said ash tray being inwardly declined from the front and top of said box and abutting at its inner end said ash remover near the center of said ash compartment, said ash remover extending from adjacent the inner end of the said cigar tray to the rear and top of said box, the plane of said ash remover being disposed at substantially 90° from the plane of said cigar tray.

plane of said ash remover being disposed at substantially 90° from the plane of said cigar tray.

6. In a smoking set, a box having an ash compartment therein, a cigar tray and an ash remover removably disposed over said ash compartment, said cigar tray being inwardly declined from the front and top of said box and abutting at its inner end said 10 ash remover near the center of said ash compartment, said ash remover extending from

adjacent the inner end of the said cigar tray to the rear and top of said box, the plane of said ash remover being disposed at substantially 90° from the said cigar tray. 15

In testimony whereof I affix my signature in presence of two witnesses.

JOHN M. ZWICKLE.
